ATTORNEYS

UNITED STATES PATENT OFFICE.

JAMES BABIN McHUGH, OF ZACHARY, LOUISIANA.

BACKBAND.

1,372,526.

Specification of Letters Patent. Patented Mar. 22, 1921.

Application filed September 8, 1920. Serial No. 408,831.

To all whom it may concern:

Be it known that I, JAMES B. McHUGH, a citizen of the United States, and a resident of Zachary, in the parish of East Baton Rouge and State of Louisiana, have invented new and useful Improvements in Backbands, of which the following is a full, clear, and exact description.

An object of the invention is to provide an improved backband for draft animals which will be comfortable to wear and which will be readily adjustable to animals of different sizes.

A further object is to provide improved means for securing the trace chains to the backband and to provide a backband which will be simple and practical in construction and yet strong and durable in use.

With these and other objects in view, the invention consists of certain novel features of construction and combinations and arrangements of parts as will be more fully hereinafter described and pointed out in the claims.

25 In the accompanying drawings,

Figure 1 is a perspective view of my improved backband with a pair of trace chains connected thereto;

30 Fig. 2 is a view in longitudinal section through the block;

Fig. 3 is a view in front elevation illustrating a modification; and

Fig. 4 is a view in longitudinal section of the modification illustrated in Fig. 3.

35 Referring in detail to Figs. 1 and 2 of the drawings, my improved backband comprises a strap 1 which is adapted to fit over the back of draft animals. One end of the strap is sewed under to form a relative small loop 2. The other end of the strap is also looped under, as shown at 3, after which it is passed through a buckle 4. The strap is preferably 40 of some woven material and the buckle 4 may be adjusted to regulate the length of 45 the strap.

Wooden blocks 5 are suspended from the ends of the strap by means of inverted U-shaped hangers 6 having their intermediate portions located in the loops 2 and 3, respectively. The arms 7 of the hangers 6 straddle the blocks 5, and pins 8 passing through the blocks 5 are mounted in perforated extrem-

ities 9 of the arms 7 whereby the blocks are pivotally supported within the hangers.

The pins 8 pass through relatively deep 55 recesses 10 which are formed in the outer faces of the blocks 5. Hooks 11 are bent to form eyes or loops 12 located around the pins 8 in the recesses 10, so that the hooks are pivotally mounted on the pins in the recesses. The free extremities 13 of the hooks project inwardly into the recesses 10.

The hooks are adapted to be swung outwardly to engage a link of the trace chains 14, and the blocks 5 serve to offset the chains 65 from the body of the animal.

In the modification illustrated in Figs. 3 and 4 I substitute for the wooden block 5 a box-like metal casing 15, preferably of bent sheet iron. The casing 15 is provided with 70 an opening 16 in its outer wall which permits the hook to swing outwardly. The operation is the same with both forms of the device.

While I have illustrated two of the preferred embodiments of my invention, it is apparent that various slight changes and alterations might be made in the general form of the parts described without departing from my invention, and hence I do 80 not limit myself to the precise details set forth but consider myself at liberty to make such slight changes and alterations as fairly fall within the spirit and scope of the appended claims.

Having thus described my invention, I claim as new and desire to secure by Letters Patent:

1. A backband, comprising a strap, a pair 90 of hangers suspended from the ends of the strap, housings suspended from the hangers, pins pivotally connecting the hangers and housings, and hooks mounted on the pins in the housings.

2. A backband, comprising a strap, a pair 95 of hangers suspended from the ends of the strap, housings suspended from the hangers, pins pivotally connecting the hangers and housings, and hooks mounted on the pins in the housings, said hooks having their free 100 extremities extending inwardly into the housings.

3. A backband comprising a strap, a pair of hangers suspended from the ends of the

strap, housings suspended from the hangers, devices connecting the hangers and housings, and hooks mounted on said devices in the housings.

5 4. A backband, comprising an adjustable strap having loops at its ends, inverted U-shaped hangers having their intermediate portions supported in the loops, blocks hav-

ing recesses in the outer faces thereof, the arms of said hangers straddling said blocks, pins mounted in the extremities of said arms, said pins passing through said blocks and recesses and pivotally connecting said hangers and blocks, and hooks mounted on the pins in the recesses.

JAMES BABIN McHUGH.
